UNITED STATES PATENT OFFICE.

THEODORE DEVELER, OF LANCASTER, PENNSYLVANIA.

RAILWAY-TRACK CLEANER.

No. 887,599.

Specification of Letters Patent.

Patented May 12, 1908.

Application filed September 25, 1907. Serial No. 394,594.

To all whom it may concern:

Be it known that I, THEODORE DEVELER, a citizen of the United States, residing at Lancaster, in the county of Lancaster and State 5 of Pennsylvania, have invented certain new and useful Improvements in Railway-Track Cleaners, of which the following is a specification.

This invention relates to new and useful 10 improvements in railway track cleaners and it is the object of the invention to provide a novel device of this character which may be easily carried by a car in such relation with the tracks as to clean said tracks during the 15 travel of a car.

It is a further object of the invention to provide a novel device of this character which is normally inoperative but which can be made to perform its functions by pressure 20 exerted on the portion of the mechanism on the platform of the car.

Furthermore, an object of the invention is to provide a novel device of this character which will possess advantages in points of 25 simplicity, efficiency and durability, proving at the same time comparatively inexpensive to manufacture.

With the foregoing and other objects in view, the invention consists in the details of 30 construction and in the arrangement and combination of parts to be hereinafter more fully set forth and claimed.

In describing the invention in detail, reference will be had to the accompanying drawings 35 forming part of this specification wherein like characters denote corresponding parts in the several views, in which—

Figure 1, is a view partly in elevation and partly in section of the front of the car illustrating the invention applied thereto; Fig. 2, 40 is a fragmentary view in side elevation of a car illustrating the invention; and Figs. 3 and 4 are detail views of certain features of the invention.

In the drawings 1, denotes a car of any ordinary or preferred construction which is intended to travel on the tracks 2, which in this instance are illustrated as L tracks, although it is to be observed that these tracks 45 may be of any character desired.

Depending from the under surface of the front platform of the car 1, in advance of the wheels and in alignment therewith, are the brackets 3. Each of the brackets has pivot- 50 ed at its lower end a lever 4, which extends to

either side of said bracket. On the outer end of the lever 4, is a plow 5, which has its point of the same configuration as the surface of the track 2. To the opposite or inner end of the lever 3, is pivotally secured a link 6, which extends upwardly through a perforation 7, in the platform of the car and is pivotally secured to a lever 8, which is arranged transversely of the platform. This lever 8, is pivoted intermediate its length to the bracket 9, 60 secured to the platform of the car. The inner end of this lever 8, is pivotally secured to a button 10.

The button 10, is provided with a hollow shank 11, which extends within the housing 70 12, secured to the platform. Bearing against the base of the housing and the under surface of the button 10, within the housing and within the hollow shank 11, is a coiled spring 13, which holds the button normally elevated 75 and at the same time holds the plow 5, away from the track.

The operation of the device is believed to be apparent without a detail thereof, it being stated, however, that when it is desired 80 to place the plow in operative position, it is only necessary to depress the button 10. While it has been stated that the device just described is on the front platform of the car, it is obvious that a similar mechanism can be 85 placed on both ends of the car for reasons which are believed to be apparent.

To further assure a thorough cleansing of the tracks each of the levers 4, has positioned thereon slightly to the rear of the plow 90 5, a brush 14, which contacts with the tracks and is intended to sweep off any of the particles loosened by the plow.

What I claim is:

1. In combination with a car and its 95 tracks, brackets depending from the car, levers pivoted intermediate their length within the brackets, plows carried by one end of the levers, brushes on the levers adjacent the plows and means engaging the 100 opposite end of the levers for forcing the brushes and plows in engagement with the track.

2. In combination with a car and its 105 tracks, brackets depending from the car, levers pivoted intermediate their length within the brackets, plows carried by one end of the levers, brushes on the levers adjacent the plows, means engaging the opposite 110 end of the levers for forcing the brushes and

plows in engagement with the track, and means for holding the brushes and the plows normally elevated.

3. In combination with a car and its tracks, 5 brackets depending from the car, levers pivoted intermediate their length within the brackets, plows carried by one end of the levers; brushes on the levers adjacent the plows, means engaging the opposite end of 10 the levers for forcing the brushes and plows in engagement with the track, links pivotally secured to the opposite ends of the levers, second levers pivoted intermediate their length to the platform of the car and extending transversely thereof, the links being pivoted to one of said second levers, a button, 15 the opposite ends of said second lever being pivoted to the button, a housing on the platform, a hollow shank on the button extending within the housing, a spring within the housing and hollow shank bearing against the button in the base of the housing for holding the button normally elevated.
- 20 4. In combination with a car and its tracks, brackets depending from the car, levers pivoted intermediate their length within the brackets, plows carried by one end of the

levers, brushes on the levers adjacent the plows, means engaging the opposite end of 25 the levers for forcing the brushes and plows in engagement with the track, links pivotally secured to the opposite ends of the levers, second levers pivoted intermediate their length to the platform of the car and extending transversely thereof, the links being pivoted to one of said second levers, a button, 30 the opposite ends of said second lever being pivoted to the button, a housing on the platform, a hollow shank on the button extending within the housing, a spring within the housing and hollow shank bearing against the button in the base of the housing for holding the button normally elevated.

In testimony whereof I affix my signature 40 in presence of two witnesses.
